UNITED STATES PATENT OFFICE.

FRANK T. KENT, OF ROME, NEW YORK.

ATTACHMENT FOR PHONOGRAHS.

1,293,797.

Specification of Letters Patent. Patented Feb. 11, 1919.

Application filed November 15, 1916. Serial No. 131,521.

To all whom it may concern:

Be it known that I, FRANK T. KENT, a citizen of the United States, and resident of Rome, county of Oneida, State of New York, have invented certain new and useful Improvements in Attachments for Phonographs, of which the following is a specification.

This invention relates to phonographs and more particularly to means for modifying the tone which is transmitted from the sound box.

It is the object of the invention to provide a device which may be readily applied to the standard types of phonographs and which when so applied will improve the quality of the reproduction by reducing or eliminating the metallic and mechanical sounds.

Other objects and the features of novelty will be apparent from the following description taken in connection with the accompanying drawings, in which,

Figure 1 is a plan view of the sound tube and sound box of a well-known type of phonograph;

Fig. 2 is an enlarged fragment of Fig. 1 with the sound tube shown in section and provided with my improvement;

Fig. 3 is a view similar to Fig. 2 but showing another form of the invention;

Fig. 4 is a perspective view of the attachment shown in Fig. 2;

Fig. 5 is a section showing a slight modification of Fig. 3.

Referring to the drawings, 10 indicates the sound tube which carries at the end 11 a goose-neck 12, this goose-neck having a swivel connection with the end 11 and constituting a continuation of the sound tube.

40 A sound-box 13, which may be of any preferred construction, is mounted on the end 14 of the goose-neck 12.

I have discovered that by placing a plug or diaphragm such as is indicated at 16, in the end 14 of the goose-neck, near the sound-box 13, and providing a central perforation in this diaphragm, the sounds emanating from the sound-box 13 will be greatly muffled. I have also found that by inserting a miniature megaphone or sound amplifier 17 in the said perforation in the diaphragm 16, the sounds will be restored to substantially the normal volume but the harsh mechanical sounds will be largely eliminated, thereby giving greater prominence to the sounds that are reproduced from the record and making the reproduction more natural. As will be observed from Fig. 2, the amplifier 17 projects from the diaphragm or partition 16 into the goose-neck, in the direction of movement or propagation of the sound waves. Care should be exercised, however, to have the amplifier 17 out of contact with the goose-neck 12 and thus supported entirely by the diaphragm 16, which should be of non-resonant material such as rubber so as to constitute a non-resonant connection between the goose-neck and the amplifier.

It will be observed that the sound box 13 may be readily removed from or replaced on the goose-neck 12 and when removed the diaphragm with the amplifier 17 may be readily inserted or removed from the position shown in Fig. 2.

Referring to the form of the invention illustrated in Fig. 3, it will be observed that this construction comprises the well-known rubber disk 18 which is attached directly to the end of the goose-neck 12 and has secured thereon, by means of screws 19, the sound-box 20. I arrange between the disk 18 and the sound-box a diaphragm 21 having a small central aperture 22 in which a miniature megaphone or sound amplifier 23 is secured. The amplifier 23 projects through the disk 18 into the goose-neck 12 and operates in substantially the same manner as the amplifier 17 shown in Fig. 2.

In Fig. 5 the modification consists in making the disk 21' integral with the disk 18' so that the sound amplifier 23 will be carried by the disk 18' and the separate diaphragm 21 shown in Fig. 3, eliminated.

It will be noted that the receiving end of the amplifier, in the different forms of the invention, is relatively small and located close to the sound box and it seems that this location produces much more satisfactory results than when the amplifier is at a position in the sound tube, more remote from the sound-box.

While I have illustrated a particular form of sound-box and sound amplifier it will be understood that the drawings are somewhat diagrammatic and that various changes in the proportions and shape of the parts may be made without departing from the spirit of the invention as defined in the appended claims.

Having described the invention what is claimed is:

1. In apparatus of the class described, the combination of a sound conduit, a sound box detachably mounted on one end of said conduit, a sound amplifier projecting into said end of the conduit and through which the sounds are conveyed from said sound box, and non-resonant means through which said amplifier is supported in said conduit. 45
2. In apparatus of the class described, the combination of a sound conduit, a non-resonant member supported at one end of said conduit and provided with a central longitudinal perforation, a sound amplifier carried by said member and projecting into said sound conduit, and a sound box on said end of the conduit and from which the sounds are transmitted to the sound conduit 50 by said amplifier. 55
3. In apparatus of the class described, the combination of a sound conduit, a source of sound connected therewith, a non-resonant partition across said conduit and having a 60 perforation extending longitudinally of the conduit, and a sound amplifier secured in said perforation. 65
4. In apparatus of the class described, the combination of a sound conduit, a source of sound connected therewith, a non-resonant partition across said conduit and having a 65 perforation extending longitudinally of the conduit, and a sound amplifier secured in said perforation and supported entirely by 70 said partition. 75
5. In apparatus of the class described, the combination of a sound conduit, a source of sound connected therewith, a non-resonant partition across said conduit and having a 80 perforation extending longitudinally of the conduit, and a sound amplifier secured in said perforation and projecting from said partition in the direction of movement of the sound waves. 85
6. In apparatus of the class described, the combination of a sound conduit, a sound box detachably mounted on one end of said conduit, a non-resonant partition fitting the interior of said end of the conduit and provided with a perforation extending longitudinally of the conduit, and a sound amplifier secured in said perforation. 90
7. In apparatus of the class described, the combination of a sound conduit, a sound amplifier supported in said conduit by means constituting a non-resonant connection therebetween, and a sound box detachably mounted on said conduit and transmitting sound through said amplifier to the conduit. 95
8. In apparatus of the class described, the combination of a member made of non-resonant material and adapted to fit the interior of a sound conduit, said member having a central perforation, and a funnel-shaped sound amplifier projecting from one side of said member and having the smaller end thereof arranged in said perforation. 100
9. As a new article of manufacture, a substantially cylindrical member made of non-resonant material and provided with a central longitudinal perforation and a funnel-shaped member made of resonant material, and having its smaller end secured in said perforation. 105
10. In apparatus of the class described, the combination of a sound conduit, a member made of non-resonant material and detachably arranged on the end of said conduit, a sound box detachably secured to said member, a disk arranged between said member and said sound box, and having a central perforation, and a funnel-shaped sound amplifier having its smaller end secured in said perforation and supported wholly by said disk. 110

In testimony whereof I affix my signature.

FRANK T. KENT.
